UNITED STATES PATENT OFFICE.

THOMAS F. WILLIAMS, DONALD W. COY, AND HARRY B. PRUDEN, OF CHICAGO, ILLINOIS, ASSIGNORS TO POWDERED COAL ENGINEERING AND EQUIPMENT COMPANY, OF CHICAGO, ILLINOIS, A CORPORATION OF DELAWARE.

APPARATUS FOR CARBURETING AIR.

1,409,325.

Specification of Letters Patent. Patented Mar. 14, 1922.

Application filed August 26, 1918. Serial No. 251,582.

To all whom it may concern:

Be it known that we, THOMAS F. WILLIAMS, a subject of Great Britain, DONALD W. COY, and HARRY B. PRUDEN, citizens of the United States, all residing at Chicago, in the county of Cook and State of Illinois, have invented certain new and useful Improvements in Apparatus for Carbureting Air, of which the following is a specification.

Prior to our invention air charged with powdered coal has been used as a fuel in various types of furnaces to which it is particularly adapted. It has been found difficult or impossible, however, to so regulate the air and coal and the mixture thereof as to produce a slow "lazy" flame of large volume in which combustion sets in close to the burner and continues throughout the body of mixed air and coal so that combustion is practically completed within a relatively short distance of the burner; and it has further been found difficult or impossible in the previously known apparatus for burning powdered coal to maintain the proper proportion of fuel and air while varying the volume of the mixture according to the varying demands made upon the apparatus. It is the purpose of our invention to provide an apparatus for mixing the powdered fuel and air in such manner that when properly fed to the furnace it will produce a slow lazy flame suitable for a great variety of uses, and which will maintain the proper mixture of air and fuel though the amount of the mixture varies within wide limits.

In the accompanying drawings we have shown a preferred embodiment of our invention and in the following specification specifically describe the same. It is to be understood, however, that the specific disclosure is for the purpose of exemplification only, and that the scope of the invention is defined in the following claims in which we have endeavored to distinguish it from the prior art so far as known to us without, however, relinquishing or abandoning any portion or feature thereof.

Referring now to the drawings, Fig. 1 shows in side elevation, partly in section, a preferred embodiment of our invention; Fig. 2 a plan thereof; Fig. 3 a vertical section of a portion of the apparatus on the line 3-3 of Fig. 2; Fig. 4 a vertical section

on an enlarged scale of a portion of the apparatus, parts being shown in elevation; and Fig. 5 an enlarged vertical section of a detail, parts being broken away to permit a larger scale to be used.

Each part is identified by the same reference character wherever it occurs throughout the several views.

Referring to Fig. 1 the different mechanisms constituting the carbureting apparatus are preferably mounted on a common base 6 and enclosed, except for the carbureter proper 7, in a casing 8 thus constituting a compact unit which may be transported as an entirety and set up where required for use. The apparatus comprises a fuel chamber 9 to which the powdered fuel is supplied in bulk, a continuous feed mechanism 10 by which the fuel is continuously fed to a chamber 11 where it is mixed with the first proportion of air, and a carbureter 7 in which an additional supply of air is furnished to the mixture bringing the proportion of air up to that considered most desirable for producing the particular character of flame desired. The apparatus also comprises a fan 12 for furnishing the air, a pair of electric motors 13, 14, and an automatic regulating device 15 by which the currents driving the respective motors are so regulated as to give the proper proportion of air and powdered fuel within a wide range of supply of the combustible mixture.

The fuel chamber 9 is supported from the base on a suitable standard 16 and is provided with a collar 17 outside the casing and communicating with said chamber, said collar being preferably so designed as to receive the package or container of powdered fuel which is applied thereto in such manner that the fuel in the container feeds continuously into the chamber 9 until said container is emptied. A conduit 18 is cast integral with chamber 9 and extends horizontally therefrom to the mixing chamber 11. A screw conveyer 19 extends through the conduit and through the bottom of the fuel chamber 9 and to the left of the same, as seen in Fig. 3, and outside the chamber 9 is provided with a worm wheel 20 for driving it. As seen more clearly in Fig. 5 the worm wheel and the end 21 of the conveyer shaft are covered by a cast metal housing 22 which is fitted to the opening 23 in the fuel

chamber through which the shaft extends and suitably secured to the wall of said chamber. Casting 22 comprises a neck 24 intermediate the worm wheel chamber 25 and flange 26 by which the casting is secured to the fuel chamber wall. Within the neck is a packing 27 of compressible material and a washer 28 bears on said packing and is forced against the same by a spring 29 intermediate said washer and a screw sleeve 30 adjusted into the neck 24. The sleeve is held in adjusted position by a finger 31 secured to the housing by a screw 32 and extending into one of a plurality of notches 33 formed on the flanged end of the sleeve. Said sleeve also forms a seat for a roller bearing 34 for the shaft 21. The housing is provided with an inspection opening 35 and cover plate 36. A worm shaft 37 is suitably journaled in the housing and meshes with said worm wheel and outside the housing is connected to and driven by the armature of the electric motor 13. See Fig. 2. Obviously, the motor through the connections indicated drives the conveyer screw 19.

The chamber 11 is in the particular embodiment of the invention shown formed of two conical castings 38, 39, united at their bases by flanges 40, 41, on the respective castings, casting 38 being connected to and communicating with conduit 18, and casting 39 comprising an enlarged conduit 42 by which the primary mixture of coal and air is conveyed to the opening 43 in the main casing or cover 8 from which said mixture is led by conduit 44 to the carbureter 7 to which reference has been made. The casting 38 is also formed with a nipple 45 which receives the end of the pipe 46, the other end of which is secured to and communicates with the casting 47 of the fan at 48, see Fig. 3. The construction of the mixer 11 is best seen in Fig. 5. The opening 49 through which the casting 38 communicates with the conveyer is shouldered at 50 to receive the flange 51 of a spout 52 by which the fuel supplied by the screw conveyer is carried to the center of the mixing chamber as at 53. The shaft 54 of the conveyer extends through the mixing chamber 11 and through an opening 55 in the wall thereof and through a packing chamber 56, the opening 55 being packed by a compressible packing 57 which is maintained under compression by washer 58 and spring 59. The outer end of the spring 59 abuts against the adjustable threaded cap 50 by which the pressure of the spring may be adjusted, said cap being locked in adjusted position by a screw 61 extending through the flange thereof. The reduced end 62 of the shaft extends through said cap at 63 and drives a rotary pump 64 by which the lubricating oil is circulated in a manner to be presently described. Within the mixing chamber 11 the shaft carries a foraminous

basket or screen 65 of the general shape of the mixing chamber but of sufficiently small size to provide clearance. Said screen is supported by arms 66 from a sleeve 67 surrounding said shaft and clamped thereto by a clamp collar 68. The screen is also formed with a reduced neck 69 which surrounds the spout 53 so that the latter discharges into the basket within the mixing chamber. Thus the screen receives a continuous stream of fuel from the chamber 9, and the mixing chamber 11 a continuous influx of air from the fan, the latter penetrating the screen and taking up the powdered fuel as fast as it is fed and conveying it out of the screen and mixing chamber through the conduit 42. From the conduits 42 and 43 the primary mixture of air and powdered fuel is discharged into the carbureter 7 where it receives an additional supply of air from the branch conduit 69^a. The latter opens from conduit 46 as shown in Fig. 3. The specific matter of the carbureter 7 is not material for the purpose of this application but we have shown it as of the construction shown in our pending application for Patent No. 124,692, filed October 9, 1916, as a renewal of application No. 70,832.

The fan 12 by which the air is furnished may be of any suitable or desired construction and is driven by the motor 14 as heretofore stated.

We have adverted to the desirability of maintaining constant the proportion of powdered fuel to air, but it has been found in practice that this proportion cannot be maintained where the supply of carbureted air is to be varied by maintaining the relative speeds of the endless conveyor and fan. In other words it is necessary not only to vary the speeds of fan and conveyor respectively, but to vary them with respect to each other and it is necessary to delicately and accurately control their respective speeds if the composition of the carbureted air is to be maintained constant. For this purpose we provide means for automatically maintaining the desired ratio of speed of the motors and said means may be operated by hand or if desired automatically controlled according to the temperature or other condition to be maintained by the burners to which the fuel is supplied. The mechanism for accomplishing this is best shown in Figs. 1 and 4. In the particular form of the apparatus chosen to illustrate our invention we provide each of the motor circuits with a carbon rheostat 70, 71, the conductivity or resistance of which varies according to the pressure applied thereto. The pressure applied to the respective rheostats is governed by a common movable part which in the specific construction illustrated is a generally cylindrical bar 72 of generally cylindrical form, except as hereinafter described, 130

so mounted as to be adjustable vertically and longitudinally according to the volume of carbureted air required. For this purpose the ends of the bar are pivoted at 73, 74 in pin and slot connections to bell crank levers 75, 76 respectively by pin and slot connections which permit a slight movement of the pivots longitudinally of the levers, and said levers are respectively pivoted at 77, 78 to the frame work of the apparatus. By reason of the pin and slot connections the bar may be given a right line longitudinal movement and for this purpose the rear edge of the bar is guided by rollers 79, 80 against which the bar is yieldingly pressed as will presently be seen. Thus the bar may be said to float with respect to the levers 75, 76. The movable outer elements of the respective rheostats are connected to rollers 82, 83 which respectively bear on the longitudinal movable bar the edge 81 of which is formed to suitably adjust the respective rheostats through said rollers. The rollers are mounted on the levers 90, 91 respectively, which levers are pivoted at 92, 93 to the frame and formed with fingers 96, 97 between which the spring 98 is compressed to force the rollers into contact with the edge of the bar 72. The axles 94, 95 of the rollers extend beyond the bifurcated levers 90, 91 and are engaged by the yokes or forks 84, 85 respectively. The yokes are adjustable upon the shanks 88, 89 of the outer members of the respective rheostats by means of the set nuts 86, 87. The rheostat 70 is connected in the circuit of the motor driving the screw conveyor by terminals 70^a, 70^b in an obvious manner and similarly the rheostat 71 is connected in the supply circuit of the motor which drives the fan by terminals 71^a, 71^b. The edge of the rod 72 at the portions 99, 100 thereof which engage the respective rollers 82, 83 is cammed or cut away to a shape to operate the rollers as the rod descends in a direction to compress the respective rheostats and so increase the current through the respective motors. The edge of the rod is not, however, of such shape as to move the rollers inwardly to the same degree but the portions thereof traveled by the respective rollers are so shaped as to regulate the resistance of the rheostats and hence the current through the motors and the speed of the motors, so that while the volume of the mixture of air and fuel is increased by the lowering of the rod, the relative proportion of fuel to air is maintained constant. We have found it necessary to determine empirically the proper shapes of these portions of the rod to effect this result.

As heretofore stated, the regulating rod may be operated manually or automatically. Preferably, however, it is operated automatically. For this purpose the bell crank 75

is urged by spring 101 in a direction to lower the rod, the spring being attached at one end 102 to a stationary part of the framework and at the other end to a bolt 103 which is adjustably mounted in the lever at 104 and may be adjusted by the thumb nut 105 to vary the tension of the spring. The bell crank 76 which is pivoted to the lower end of the rod is likewise under spring pressure but in the opposite direction. For this purpose a link 106 is pivoted at 107 to bell crank 76 and at its other end to a bell crank 107^a to which is attached one end of spring 108. The other end of said spring is attached to an internally threaded sleeve 109 which receives an adjusting screw 110. Said screw may be turned to adjust the tension on the spring by means of a handwheel 111 connected to said screw outside the casing. The particular medium for automatically actuating the regulating rod 76^a depends upon the use to which the apparatus is put. Where the generation of steam is concerned one manner of effecting the regulation and that shown in the drawings utilizes a bellows 112 which is enclosed in a casing 113 and connected by rod 114 to the lower end of the regulating bar. The boiler pressure is in communication with the bellows 112 through the steam pipe 115 which communicates with the bellows at 116. Obviously as the pressure rises the bellows expands raising the rod and correspondingly releasing the pressure on the rheostats, thereby increasing the resistance and lowering the speed of the motors. As the pressure falls the bellows collapses correspondingly, dropping the rod, reducing the resistance and speeding up the motors. Obviously the connections of the bell cranks to the rod must be slightly slotted or elongated as shown in order to provide for an arcuate movement of the bell cranks and a straight-line movement of the rod. At 124 we have indicated a backing for a switchboard.

At an earlier portion of the specification we have referred to the pump 64 by which the oil is circulated. The suction side of this pump is connected by pipe 125 to an oil reservoir 126 and the exhaust side of the pump is connected by a pipe 127 to branches leading to the various mechanisms requiring lubrication. Branch 128 leads to the housing or chamber 56 which is kept full of oil, thereby lubricating the shaft bearing 129 therein and keeping the packing saturated. From chamber 56 the oil is returned by pipe 130 to the oil reservoir. Another branch 131 leads from the main 127 to the casing 25 which contains the gearing for driving the screw conveyor and from said casing the pipe 132 leads to a return main 133 by which the oil reaches the reservoir. If desired the bearings of the motors may be supplied with oil through the supply main 130.

127 and the oil returned by return main 133, the connections for this purpose being shown at 134 and 135.

Our invention provides an entirely automatic, or if desired manually operated, system by which a burner or series of burners may be supplied with carbureted air, the proportions of the ingredients being maintained constant irrespective of the quantity, whereby the character of the flame or flames may be maintained unchanged notwithstanding the fact that the heat units may be varied greatly. Obviously the apparatus is not limited to the maintenance of a particular degree of pressure though it is well adapted for this purpose. For example, it may equally well be used for the maintenance of a constant temperature in a building or elsewhere, the regulating bar in this case being actuated by a suitable thermostat, the construction of which instrument is well known. Again the broad principle involved in our invention is obviously applicable to the control of motors other than electric. Thus if fluid motors are employed mechanism for controlling the flow of the fluid would be substituted for the rheostats described. By our invention also it is possible to closely control the character of the flames produced by the mixture, and this is of particular importance where the apparatus is used for metallurgical purposes for many of which the chemical character of the flame reducing or oxidizing is important.

35 We claim:

1. In a device of the class described, a mixing chamber, means for feeding air in variable quantities thereto, means for feeding powdered material in variable quantities thereto, separate motors for the respective feeding means, means common to both said motors for varying the speed thereof in accordance with the demands on the device and differentially with respect to each other.
- 45 2. In a device of the class described, a mixing chamber, a blower for supplying the same with air, a motor for operating the blower, a continuously operating conveyor for supplying the mixing chamber with fuel, a motor for operating the conveyor, means for supplying power to the respective motors, and common means for differentially increasing and diminishing the supply of power to the motors.
- 55 3. In a device of the class described, a mixing chamber, a blower for supplying the same with air, a continuously operating conveyor for supplying the chamber with powdered fuel, a motor for driving the blower, a motor for driving the conveyor, independent means for controlling the supply of power to the respective motors, a common movable element operating differentially on the respective means for controlling the supply of power and means for adjusting the

last said means according to the amount of mixture to be produced.

4. In a device of the class described, a mixing chamber, a blower for supplying the same with air, a continuously operating conveyor for supplying the chamber with powdered fuel, motors for the blower and conveyor respectively, independently adjustable means for controlling the supply of power to the respective motors, and a movable element common to said adjustable means for differentially regulating the same.

5. In a device of the class described, a mixing chamber, a blower for supplying the same with air, a conveyor for continuously supplying the chamber with powdered fuel, electric motors for the blower and conveyor respectively, rheostats controlling the supply of current to the respective motors, a regulating bar common to the rheostats and adapted to simultaneously and differentially adjust the same, and means for moving the bar in accordance with the amount of mixture to be delivered.

6. In a device of the class described, a mixing chamber, a blower, a fuel conveyor, electric motors for the blower and conveyor respectively, rheostats for the respective motors the resistance of which is varied according to pressure, a movable element common to the rheostats formed with eccentric surfaces differentially controlling the pressure on the rheostats, and means for moving said element in accordance with the demand for the mixture of air and fuel.

7. In a device of the class described, a blower, a continuously operating conveyor, a mixing chamber to which said blower and conveyor feed, electric motors for the blower and conveyor respectively, compression rheostats for controlling the supply of current to the respective motors, said rheostats comprising movable means for controlling the pressure thereon, a bar common to said movable means of the respective rheostats and having differentially cammed surfaces for engaging the respective movable means, and means for moving said element in accordance with the amount of mixture desired.

8. In a device for supplying a boiler furnace with carbureted air, a mixing chamber, a continuously operating conveyor for supplying the mixing chamber with powdered fuel, a blower for supplying the mixing chamber with air, motors for driving the blower and conveyor respectively, means for controlling the power delivered to the respective motors comprising a movable element provided with differential surfaces controlling the supply of power to the respective motors, and means operated by the boiler pressure for adjusting said element.

9. In a device of the class described, a mixing chamber, a conveyor for continuously conveying powdered fuel thereto, a

blower for delivering a continuous stream of air to the chamber, electric motors for operating the blower and conveyor respectively, rheostats for the respective motors, 5 means for differentially operating the rheostats comprising a bar having cammed surfaces thereon and connections operated by the respective cammed surfaces for exerting

pressure upon the respective rheostats, pivoted levers to which said bar is attached at 10 its pivoted ends, springs tending to move said levers, and means for adjusting the tension of the springs.
